DESIGN FOR A GARDEN WORK AND SPORT SHOE

Delia F. Whatmore, Seattle, Wash.

Application April 25, 1949, Serial No. 2,237

Term of patent 14 years

(Cl. D7—7)

To all whom it may concern:

Be it known that I, Delia F. Whatmore, a citizen of the United States, residing at Seattle, in the county of King and State of Washington, have invented a new, original, and ornamental Design for Garden Work and Sport Shoe, of which the following is a specification, reference being had to the accompanying drawing forming part thereof.

The figure is a perspective view of a garden work and sport shoe, showing my new design, the opposite side presenting substantially the same appearance as the side shown.

I claim:

The ornamental design for a garden work and sport shoe, substantially as shown and described.

DELIA F. WHATMORE.
